UNITED STATES PATENT OFFICE.

EDWIN W. SEEGER, OF MILWAUKEE, WISCONSIN, ASSIGNOR TO THE CUTLER-HAMMER MFG. CO., OF MILWAUKEE, WISCONSIN, A CORPORATION OF WISCONSIN.

CONTROL SYSTEM FOR PRINTING PRESSES.

Application filed July 11, 1925. Serial No. 42,899.

This invention relates to control systems for multi-unit printing presses and similar mechanisms.

In the application of Thomas H. Rodman and Paul W. Darlington, Serial No. 646,052, filed June 18, 1923, there is disclosed a control system for multi-unit printing presses including a plurality of separately operated circuit controlling switches for effecting control commutations to suit various driving combinations between the driving and driven units.

The present invention has among its objects to provide a system of the aforesaid character including a single operating means adapted to act on all of the circuit controlling switches to effect selected settings thereof to suit the various drive combinations.

Another object is to provide means of the aforesaid character including a control part adapted to be set in different positions for selection of control commutations and power operated means under the control of said part for operating the switches to effect the selected control commutation.

Various other objects and advantages of the invention will hereinafter appear.

The accompanying drawings illustrate an embodiment of the invention which will now be described, it being understood that the embodiment illustrated is susceptible of modification without departing from the spirit and scope of the appended claims.

In the drawing:

Figure 1 is a schematic view of a plurality of driven units and drives therefor to which control commutating means embodying the invention may be applied;

Fig. 2 is a schematic and diagrammatic view of the driven units and the driving motors therefor together with commutatable control means for the motors;

Fig. 3 is a diagrammatic view showing in detail means for commutating the connections between one element of a control station and the control panels of three drives;

Fig. 4 is a simplified side elevational view of the operating means for the commutating switches shown in Fig. 2;

Figs. 5 and 6 are detail views of certain of the operating cams illustrated in Fig. 4; and

Fig. 7 is an end elevational view of certain of the control parts illustrated in Fig. 5.

Referring to Fig. 1, the same shows a driven machine which may be assumed to be a printing press comprising twelve printing units A to L and folders 1 to 4, one for each group of three printing units. Each printing unit may be assumed to be designed to print eight pages, and each group of three printing units and the folder therefor is provided with a double motor drive, although it is, of course, to be understood that the number of units in each group may be either decreased or increased as desired.

As illustrated the group of printing units A, B and C and folder 1 has a drive M' comprising a large motor 6 and a small motor 7, said motors driving through a chain 8 and sprockets 9 and 10, a countershaft 11 having a slip gear 12 to mesh with a gear 13 on shaft 14 to which the aforementioned driven units and folder are connected. The printing units A, B and C and folder 1 are each connected to shaft 14 by a set of bevel gears, one gear of each set being slidable on said shaft to disconnect its respective unit from said shaft. The remaining groups of printing units and folders are respectively provided with like motor drives M², M³ and M⁴ which drive through like connections the shafts 15, 16 and 17 of said groups. Each motor drive is preferably designed to be capable of driving as many as six printing units and one folder and the shafts 14, 15, 16 and 17 are provided with couplings therebetween and between sections thereof whereby the motors may be so employed, and, moreover, employed alternatively.

More specifically, the shafts 14 and 15 have a coupling 18 therebetween, while the shafts 15 and 16 have a coupling 19 therebetween and shafts 16 and 17 have a coupling 20 therebetween. Further, the shaft 15 is interrupted between units D and E and has its respective gear 13 rotatably mounted on one section thereof to be coupled to the two sections of said shaft selectively or to both by

couplings 21 and 22. Similarly, the shaft 16 is interrupted between units H and I and its respective gear 13 is revolubly mounted on one section and provided with couplings 23 and 24 to connect the same to the two sections of said shaft selectively or to both. The commutatable driving connections described enable the units to be operated as four sextuple presses each to print a twenty four page paper, or alternatively, as three octuple presses each to print a thirty two page paper, or alternatively as two dessuple presses each to print a forty page paper, or alternatively as two sextuple presses each to print a forty eight page paper. Moreover each of the aforementioned presses of four or more units may be driven by either of a plurality of drives selectively. From the foregoing, it is apparent that the aforescribed combinations may be tabulated as follows:

	Combination.	Press.	Drive.	Folder.
25		[ABC] [DEF] [GHI] [JKL]	1 2 3 4	F1 F2 F3 F4
1		[ABCD] [EFGH] [JKL]	1 2 3 4	F2 F3 F4
30	2	[ABCD] [EFGH] [JKL]	1 2 3 4	F2 F3 F4
3		[ABCD] [EFGH] [JKL]	1 2 3 4	F2 F3 F4
40	4	[ABCD] [EFGH] [JKL]	1 2 3	F2 F3 F4
35	5	[ABCD] [EFGH] [JKL]	2 3 4	F2 F3 F4
6		[BCDEF] [HIJKL]	1 2	F2 F4
40	7	[BCDEF] [HIJKL]	2 4	F2 F4
8		[BCDEF] [HIJKL]	1 4	F2 F4
9		[BCDEF] [HIJKL]	2 3	F2 F4
45	10	[ABCDEF] [GHIJKL]	1 3	F2 F4
11		[ABCDEF] [GHIJKL]	2 4	F2 F4
12		[ABCDEF] [GHIJKL]	1 4	F2 F4
50	13	[ABCDEF] [GHIJKL]	2 3	F2 F4

Referring to Fig. 2, the same shows the printing units folders and drives together with control panels C¹, C², C³ and C⁴ for the drives M¹ to M⁴, respectively; control stations S, one of each printing unit and folder, and switches 30 to 42, inclusive, for effecting control commutations in accordance with the aforescribed mechanical commutations. As will be understood the control station of each printing unit and folder must be given control over the drive to which such unit or folder is coupled, and, as will be apparent from the aforescribed mechanical

commutations, certain of the stations must be connected to any one of three drives.

Each of the switches 30 to 42 has two positions to which it may be moved selectively, one position being indicated by the full line 70 extending obliquely from the right hand side thereof and the other position being indicated by the dotted oblique line. Each switch when positioned as indicated by the full line, connects the cable leading thereto 75 from the left to the cable, if any, leading from the upper end thereof, while in the absence of the latter cable the switch disconnects the former cable from circuit. On the other hand, each switch when positioned as 80 indicated by the dotted line, connects the cable leading thereto from the left to the cable leading from its lower end.

Referring to Fig. 3, the same shows a control station S with one control circuit leading therefrom and means for connecting said circuit to the appropriate terminal of any one of three control panels, which may be assumed to be panels C¹ C² and C³. The commutating switches may be assumed to be 90 switches 35 and 36 each having omitted therefrom all contacts except those required for commutating the single control circuit illustrated, which is typical of the circuits to be commutated as between one control station and any three control panels. The switch 35 in the position shown connects the station S to switch 36 and the latter connects said station to control panel C³. On the other hand by moving switch 36 to its dotted line 95 position the circuit from the control station may be shifted to panel C¹ and by moving the switch 35 to its dotted line position, said circuit may be shifted to panel C². Thus Fig. 3 in conjunction with Fig. 2 serves to 105 disclose fully all electrical commutations necessary to meet the requirements of the mechanical commutations aforescribed.

The commutating switches 30 to 42 inclusive are arranged side by side and each is biased to its dotted line position indicated in Fig. 2. As shown in Fig. 4, the operating member of each of the commutating switches has an operating cam associated therewith, said cams being designated by reference character "a" and all of the same being fixed to a shaft 45. Shaft 45 is rotatable and has 110 13 angular positions corresponding to the drive combinations hereinbefore tabulated. The several cams are so shaped that when shaft 45 is in a position corresponding to a given drive combination, proper setting of the commutating switches is obtained. For example, in the foregoing tabulation press E is connected to drive 1 in combinations 6, 120 8, 10 and 12 to drive 2 in combinations 1, 3, 4, 7, 9, 11 and 13 and to drive 3 in combinations 2 and 5. To provide the proper control commutations for these drive combinations, commutating switches 35 and 36 are 125 130

provided with cams which are shaped as shown in Figs. 5 and 6. Cam 35^a is provided with projections for raising the operating member of its respective switch in positions 2, 5, 6, 8, 10 and 12 of shaft 45, while cam 36^a is provided with projections for raising the operating member of its respective switch in positions 2 and 5 of said shaft. It is thus apparent that in positions 1, 3, 4, 7, 9, 11 and 13, commutating switch 35 is in its dotted line position Fig. 3 to connect station S of press to E to the panel C². In positions 2 and 5 of shaft 45 both of the commutating switches 35 and 36 are held in their full line position Fig. 3, to connect station S of press E to panel C³, while in positions 6, 8, 10 and 12 commutating switch 35 is held in its full line position and commutating switch 36 in its dotted line position to connect station S of press E to control panel C¹. The other operating cams are designed in the same manner as the aforescribed cams to hold their respective commutating switches in the proper position for the drive combinations hereinbefore tabulated.

Shaft 45 is adapted to be driven by a motor M having an armature A and a series field winding F. Motor M, is supplied with current from lines L¹ and L² through the medium of an electromagnetically operated double pole switch 47 and the energizing circuit of said switch is controlled by a selector device 48. Selector device 48 includes a contact element 49 fixed to shaft 45 and a cooperating selector element 50 rotatably mounted on said shaft. As best shown on Fig. 7 contact element 49 has a cooperating contact finger 51, and is provided with an insulated section 52. Selector member 50 carries a contact 53 which is normally in engagement with the insulated section 52 and contact 53 is connected to line L¹ while contact 51 is connected to line L² through the operating winding 47^a of switch 47.

Assuming that selector device 48 is in the position shown in Fig. 7, movement of the selector element 50 in clockwise direction, energizes switch 47 through the medium of contacts 49 and 52 to establish power connections for operation of the motor in a clockwise direction. The degree of operation of the motor is determined by the degree or movement of the selector element 50. In other words the insulated portion 52 will always interrupt the energizing circuit of switch 47 when the shaft 45 is brought to an angular position corresponding to the angular position of selector element 50.

What I claim is new and desire to secure by Letters Patent is:

1. In combination a plurality of driven and motor driving units, drive commutating means therebetween to connect said units in different combinations, a controller for each of said driving units, a control station

of each of said driven units, circuit commutating means between said controller and said stations including switches to connect said controllers and said stations in different combinations corresponding with the drive commutations and a common operating means for said commutating switches.

2. In combination a plurality of driven and motor driving units, drive commutating means therebetween to connect said units in different combinations, a controller for each of said driving units, a control station for each of said driven units, means for connecting said controllers and said stations in different combinations corresponding to the drive commutations, said means including a plurality of commutating switches and a single cam element for operating said switches.

3. In combination a plurality of driven and motor driving units, drive commutating means therebetween to connect said units in different combinations, a controller for each of said driving units, a control station for each of said driven units, commutatable means for connecting said controllers and said stations in different combinations corresponding with the drive commutation, said means including a plurality of commutating switches and a rotatable cam element for operating said switches, said cam element being adapted in different angular positions to effect setting of said switches to suit the drive commutation.

4. In combination a plurality of driven and motor driving units, drive commutating means therebetween to connect said units in different combinations, a controller for each of said driving units, a control station for each of said driven units, means including a plurality of separately operable switches for connecting said controllers and said stations in different combinations corresponding with the drive commutation, a cam element associated with said switches to effect setting thereof in positions to suit the drive combination and operating means for said cam element including a part adapted to be preset in any one of a plurality of different angular positions and power operated means for moving said cam element to corresponding angular positions.

5. In combination a plurality of driven and motor driving units, drive commutating means therebetween to connect said units in different combinations, a controller for each of said driving units, a control station for each of said driven units, commutating means between said controller and said stations including switches to connect said controllers and said stations in different combinations corresponding with the drive commutations, a cam element adapted in different angular positions to effect setting of said switches to suit the drive commutations, a

driving motor for said cam element, a control part adapted to be set in different angular positions corresponding to the angular positions of said cam element and means for energizing said motor upon movement of said control part from one angular position to another angular position and for deenergizing said motor upon movement of said cam element into a position corresponding to the latter position of said control part. 10
In witness whereof, I have hereunto subscribed my name.

EDWIN W. SEEGER.
